5-47

5379

57

4,518

FT, WM. B. WEEDEN & JAMES W. TAFT

DESIGN FOR WOVEN FABRICS.

4518

PATENTED DEC 13 1870

FIG. 1.

FIG. 2.

WITNESSES.

Peter H. Hughes
A. J. Cushing.

INVENTORS.

Royal C. Taft
Wm. B. Weeden
James W. Taft

United States Patent Office.

ROYAL C. TAFT, WILLIAM B. WEEDEN, AND JAMES W. TAFT, OF PROVIDENCE, RHODE ISLAND.

Design No. 4,518, dated December 13, 1870.

DESIGN FOR A WOVEN FABRIC.

The Schedule referred to in these Letters Patent and making part of the same.

all whom it may concern:

Be it known that we, ROYAL C. TAFT, WILLIAM WEEDEN, and JAMES W. TAFT, all of the city and city of Providence, in the State of Rhode Island, originated a new and useful Design for Woven fabrics; and we do hereby declare that the following description, taken in connection with the drawing being a part of the same, is a full, clear, and exact description and representation thereof.

Figure 1 is a face view of the cloth.

Figure 2 is a cross section.

Our invention resides in such a combination of said "herring-bone" parallel stripes with continuous broken-line stripes of contrasting colors, as to produce a characteristic design for fancy cassimeres.

In the drawing—

A represent parallel stripes of a raised herring-bone weave, thrown up upon a plain or a contrasting colored ground.

The stripes are bounded by two or more continuous lines, a, which will heighten the effect if shaded deeper than or in contrast with the ground color of the stripes.

Between the stripes A are broken parallel lines, b, b, which, if in different colors, as, for example, the portion c in black, and the portion d in orange, and so on alternately, will produce what is known as a mottled line, and greatly add to the attractiveness of the pattern.

What we claim as new, and desire to secure by Letters Patent, is—

The design for fancy cassimeres, consisting of the herring-bone stripes A, continuous lines a, and broken or mottled lines b, substantially as shown and described.

ROYAL C. TAFT.
WM. B. WEEDEN.
JAMES W. TAFT.

Witnesses:

PETER F. HUGHES,
A. J. CUSHING.